CITRUS FRUIT SPOON

Charles P. Schiller, P.O. Box 1367, Winter Haven, Fla.

Filed Feb. 13, 1963, Ser. No. 73,545

Term of patent 14 years

(Cl. D54—12)

FIG. 1

FIG. 2

FIG. 3

FIG. 4

FIG. 5

FIG. 6

FIGURE 1 is a rear elevational view of a citrus fruit spoon embodying my new design;

FIGURES 4, 5 and 6 are enlarged cross-sectional views taken along lines 4—4, 5—5 and 6—6 of FIGURE 3.

I claim:

The ornamental design for a citrus fruit spoon, substantially as shown.
